CONTINUOUS OXYGEN RECORDER

Clark Pettingill, Seal Beach, and Elmer J. Barlow,
Long Beach, Calif.

Application August 26, 1933, Serial No. 686,946

6 Claims. (Cl. 23—230)

This invention relates to the method and means of continuously recording the comparative amount of and variation of suspended vapors in a gaseous medium or light absorptive matter diffused in a liquid medium. The present embodiment refers more particularly to the method of continuously recording the comparative amount and variation of the oxygen content of feed water for boilers, and apparatus for the purpose.

An object of the invention is to provide apparatus responsive to variations in the amount and intensity of light received from an established source which is varied by the variable light absorptive matter content of the medium being examined and which will make a continuous record of the variations.

The method contemplated in the present invention consists in passing radiant energy, such as light, from an established source, through a stream of water, adding to the water reagents which will react with the variable oxygen content of the water to change its radiation absorption quality and cause a definite resistance to the passage of radiant energy from the source in accordance with the oxygen content of the water, again passing the radiant energy from the source through the solution and recording the variation in light absorption due to the oxygen present in the water and its reaction to the reagents. In making this method possible, means are provided whereby the variation in amount and intensity of light passing through the stream of water is caused to effect, through suitable light-sensitive devices, a balance of potentials between two electric circuits. Suitable means are provided whereby a continuous record is made of the extent to which the potentials are thrown out of balance by the variation in amount and intensity of the light directed to the light-sensitive devices.

The operative means employed and controlled by the variation between the potentials of the two circuits is also the operative means for making the record. The difference between the potentials of the two circuits is made to effect the operation of the operating means of a suitable adjustable and regulatable resistance. Movement of the parts necessary to make the record and due to the unbalance of the potentials is proportional to the variation in the amount of oxygen in the feed water. Therefore a record is made of the movement of the parts due to the unbalance of the potentials between the circuits. More particularly, movement of the resistance contact is coincident with movement of the re-

cording stylus. A suitable motor is employed to move the parts to adjust the resistance and move the stylus. The motor is controlled by a circuit making galvanometer and a relay switch.

An object of the present invention is to provide means whereby a continuous record may be made of the movement of the parts which is proportional to the amount of oxygen carried by the water being examined. Another object is to produce a continuous record which will represent the proportional amount of oxygen in the water as it flows by the observation point, and which will show the variation in the amount of oxygen. Another object is to employ and so arrange the parts that the oxygen present in the water being examined is the control element in determining the movement of the stylus which makes the record. A still further object is to provide an apparatus which is durable, reliable and not easily thrown out of adjustment.

Other objects and advantages will become more apparent from the following specification when considered in connection with the accompanying drawing, in which:

Fig. 1 is a diagrammatic representation of the complete device showing means by which the water is presented before the light-sensitive devices both before and after the reagents have been introduced, the circuits, the controlling devices, the operating means and the recording means.

Referring to the drawing with more particularity, the lamp 1, a suitable electric lamp, is used as a source of light for the examining vessels 2 and 3. A system is arranged through which sample water may flow comprising, an intake pipe 4 which enters one end of the examining vessel 2, another pipe 5 which leads out of the opposite end of the examining vessel 2 and enters the mixing chamber 6. This mixing chamber is arranged for introducing into the water suitable reagents which will react with the oxygen in the water to cause a turbid condition or a light absorptive substance which will interfere with the passage of light through the water. Though many suitable reagents are known to those skilled in this art, the one which we have found very satisfactory and employed with the present apparatus consists of two primary solutions combined in the mixing chamber 6.

The first consists of: sugar 6 oz., pyrogallic acid $\frac{1}{2}$ oz., sulphuric acid, 2.5%, 1 oz., and water to make 32 oz.

The sugar is used only to increase the specific gravity of the solution, so as to maintain a bal-

anced condition. The sulphuric acid is used only to keep the pyrogallic acid from absorbing oxygen from the air while the solution is being compounded.

5 The second solution consists of: sodium carbonate 4 oz., and water to make 32 oz.

The sodium carbonate solution is fed in sufficient quantity to neutralize the sulphuric acid in the first solution and leave an excess to make 10 the mixture alkaline. The pyrogallic acid in an alkaline solution has a great affinity for oxygen and in combination with oxygen forms a brown compound which discolors the feed water sufficiently to affect the light absorptive condition of 15 the feed water. The reagents are introduced in a suitable manner, as by a tube 7, and so as to continuously supply a predetermined proportion and amount. The water then passes through the tube 8 to the end of the examining vessel 3 and out through the tube 9. The examining vessels 3 and 2 have transparent closures 10 and 11 and 20 12 and 13 to admit of light from the common source 1 passing through the vessels to fall upon the light-sensitive devices 14 and 15, which will be more fully described as the description proceeds.

If water is allowed to flow through the examining vessels without physical or chemical change in the water between the two vessels 2 and 3, the 25 light absorptive condition of the water will be the same in each vessel and an equal amount of light will pass from the source 1 through the vessels to the light-sensitive devices 14 and 15, no matter what the actual physical or chemical 30 condition of the water may be; but if a change in the physical or chemical condition is brought about as the water passes through the mixing chamber 6 to make the water more turbid, or colored, or otherwise more light absorptive, the 35 amount and intensity of light passing through the examining vessels 2 and 3 will be unequal and the light-sensitive electric devices 14 and 15 will be affected unequally.

In the present embodiment and in the present 40 drawing and description, the light-sensitive electric cells 14 and 15 are light-sensitive generative electric cells and are the source of electric potentials in the circuits in which they are included. Such cells are well known to those skilled in this 45 art and comprise a device in which the elements are so arranged that when exposed to the direct rays of light or suitable radiant energy electric energy is generated within the cell and proportional to the amount or intensity of the light 50 received. In the circuit A, in which the cell 15 is included, is a resistance 16. In the circuit B, in which the cell 14 is included, is an adjustable resistance 17, and an adjustable resistance 18 is included as a means by which the two cells may 55 be balanced if unequal in efficiency. The circuits A and B are opposed.

If, when light from the source is passed through 60 the vessels 2 and 3 to the cells 14 and 15, and the light absorptive condition of the water in the vessels is unequal, the cells 14 and 15 will be affected unequally. If more light passes through the vessel 2 than through the vessel 3, the cell 14 will be more active than the cell 15 and generate more electricity resulting in a 65 greater potential drop across the resistance 17 than across the resistance 16.

A by-circuit C is provided connecting the positive side of the resistance 16 with the arm 19 of the resistance 17 and including a circuit making galvanometer 20. The generating cells 14

and 15 are preferably of equal resistance, equal sensitiveness and equal generative value, and the resistances 16 and 17 are of equal resistance value. When the drop across the resistances 16 and 17 is unequal and the potentials on either side of the circuit making galvanometer 20 are unequal, the galvanometer will be affected thereby and its contact arm 21 will be moved to make a contact.

The circuit making galvanometer 20 may be of any suitable type for the purpose and which is constructed to make and break circuits for the control of a relay switch. The type shown here to illustrate has a swinging contact arm 21 and two contact terminals 22 and 23, with either of which the arm 21 may make contact in its movement to bring about the closing of a circuit. The contact terminal 22 may indicate a point to which the arm 21 may swing when the potential of circuit B is greater than that of circuit A, and when the potential on that side of the galvanometer including the lead 24 and that part of the resistance 17 included in the galvanometer circuit C at the moment is greater than on the other side of the galvanometer including the lead 25.

A balance of potential across the galvanometer 20 may be made by moving the arm 19 of the adjustable resistance 17 to include in the circuit C enough of the resistance 17 to compensate for the difference in potential across the galvanometer. Movement of the arm 19 is accomplished by means including, a threaded nut 26 on the threaded shaft 27, a reversing motor 28 which, through suitable speed reducing gears, drives the shaft 27, a suitable source of energy 29, and a reversing switch 30 which is a relay switch operable by remote control and may be of any standard type suitable for the purpose.

The motor 28, the relay switch 30 and the galvanometer 20 are operably connected and associated. From the contact terminal 22 of the galvanometer 20, a conductor 31 is carried to the relay switch 30, also a conductor 32 from the contact terminal 23, and a conductor 33 from the contact arm 21. When the arm 21 swings to contact the terminal 22, a circuit through the conductors 31 and 33 is closed which operates the relay switch 30 to close a circuit with the motor 28 to start the motor in the direction to move the shaft 27 in the right direction of rotation to move the nut 26 and the resistance contact arm 19 to readjust the portion of the resistance 17 included in the circuit C to bring about a balance of potential across the galvanometer 20. When this balance of potential is restored, the contact of the arm 21 and the terminal 22 will be broken and, through the relay switch 30, the motor 28 will be deenergized and stopped. A reverse movement of the motor 28, the nut 26 and the arm 19 will be brought about if the contact is made between the arm 21 and the terminal 23 establishing a closed circuit through leads 32 and 33, and the adjustment of the resistance 17 will be in an opposite direction. Thus a balance of potential is maintained across the galvanometer 20 by a movement of the arm 19 of the adjustable resistance 17 to compensate for the difference of potential between the circuits A and B, or a difference in drop across the resistances 16 and 17. It is an object of the present invention to make a continuous record of the movement of the arm 19. This is accomplished by attaching an arm 34 to the nut 26 with a stylus 35 which rides upon

a moving record sheet 36, by which means a record, indicated as 37, is made upon the moving sheet 36.

When a contact is once made between the arm 21 and one of the terminals 22 or 23, the contact will not be broken until the balance of potential across the galvanometer has been restored, and so long as a contact is made the motor will continue to move the nut 26 and the arm 19 of the resistance 17. Therefore the movement of the arm 19 is proportional to the amount the potentials across the galvanometer are out of balance, and this is an indication of the ratio or proportional difference of potential between the circuits A and B, or between the drop across the resistance 16 and the resistance 17. This is also a measure of the ratio or proportional difference between the amount of energy generated by the cell 14 and the cell 15. As the generative value of the cells 14 and 15 depends upon the amount of light which falls upon the cells, and is proportional thereto, the movement of the arm 19 is proportional to the ratio or proportional difference between the amount of light which is allowed to pass through the vessels 2 and 3. It is also a measure of the extent to which the water in one vessel is light absorptive as compared to the water in the other vessel. As the light absorptiveness of the water in one of the vessels is directly dependent upon the amount of oxygen in the water and its reaction to the reagents introduced between the two vessels, the operation of the cells 14 and 15, the consequent difference in potential between the circuits A and B, the difference in potential across the galvanometer 20, and the movement of the arm 19 are all dependent upon and proportional to the amount of oxygen in the water and its reaction to the reagents introduced between the two examining vessels. Therefore the movement of the stylus 35 and the record 37 made by it will be proportional to the amount of oxygen in the water, and as the record sheet moves, the record 37 will be a continuous record of the variations in amount of oxygen in the water as it flows through the examining vessels.

The adjustable resistance 18 is introduced as a means for balancing the output of the cells 14 and 15, should they be unequal in generative efficiency, but other well known means may be employed for the purpose. The lamp 1 may be adjusted to bring about the same result by distribution of the light, or an adjustable screen which will partially screen one of the cells. There is variation in the amount of light which emanates from the opposite sides of otherwise standard lamps, and the lamp must be adjusted and arranged accordingly.

The parts employed in the construction of our invention and the distribution of the parts may be modified, but the description of the present embodiment conveys the operation of the device in attaining the objects sought and the relation and distribution of the parts.

Having thus described our invention, what we claim is:

1. An apparatus for making a continuous record of the oxygen content of flowing water comprising, two electric circuits opposed as to potentials, in one circuit a light-sensitive electric generative device whereby a potential drop is maintained across a resistance in that circuit, in the other circuit a light-sensitive electric generative device whereby a potential drop is maintained across another resistance, a source of light com-

mon to said light-sensitive devices, means whereby water may be interposed between said source of light and said light-sensitive devices whereby the potentials in said circuits are affected by a partial absorption of the light directed to said light-sensitive devices, means controlled by the potentials in said circuits whereby an adjustable resistance is adjusted, and means whereby a continuous record is made of the changes in adjustment of said adjustable resistance. 10

2. An apparatus for making a continuous record of the oxygen content of flowing water comprising, two electric circuits opposed as to potentials, a light-sensitive electric generative device in each of said circuits, each of said devices responsive to the amount of light absorptive substance carried in suspension in the water passing before said devices, a resistance in each of said circuits, a source of light common to said light-sensitive devices, means whereby water 20 may be interposed between the source of light and said light-sensitive devices whereby the potentials in said circuits are affected by the partial absorption of the light directed to said light-sensitive devices, a recording means, a regulatable resistance, and means controlled by the potentials in said circuits for regulating said regulatable resistance and making a continuous record directly with variations of the light absorbed. 30

3. An apparatus for making a continuous record of the oxygen content of flowing water comprising, two examining vessels constructed and arranged to allow a stream of water to flow through the vessels consecutively, means for introducing reagents into the water between the vessels to effect a change in the light-absorptive quality of the water due to the reaction of oxygen present in the water, a source of light common to said vessels, two light-sensitive electric 40 generative devices constructed and arranged to receive light through said vessels and maintain electric potentials in two opposed circuits, and means whereby a continuous record is made of the ratio between the potentials of the two circuits including, a circuit making galvanometer, a relay switch operably connected therewith and a motor. 45

4. An apparatus for making a continuous record of the oxygen content of flowing water comprising, two examining vessels constructed and arranged to allow a stream of water to flow through the vessels consecutively, means for introducing reagents into the water between the vessels to effect a change in the light absorptive 55 quality of the water due to the reaction of oxygen present in the water, a source of light common to said vessels, two light-sensitive electric generative devices constructed and arranged to receive light through said vessels and maintain 60 electric potentials in two opposed circuits, a recording means including, a motor, and means whereby the operation of said motor is controlled by and in accordance with the oxygen in the water flowing through said vessels. 65

5. An apparatus for making a continuous record of the oxygen content of flowing water comprising, two examining vessels constructed and arranged to allow a stream of water to flow through the vessels consecutively, means for introducing reagents into the water between the vessels to effect a change in the light absorptive 70 quality of the water due to the reaction of the oxygen present in the water, a source of light common to said vessels, two light-sensitive elec- 75

tric generative devices constructed and arranged to receive light through said vessels and maintain electric potentials in two opposed circuits, a recording means including, an adjustable resistance, a recording stylus, a motor operably connected with said adjustable resistance and said recording stylus, and means whereby the operation of said motor is controlled by and in accordance with the oxygen in the water flowing through said vessels.

5. The method of making a continuous record of the amount of oxygen present in flowing water which consists in, passing the water through a transparent vessel, introducing suitable reagents

such as pyrogallic acid and sodium carbonate into the water whereby the light absorptive quality of the water is changed by reaction of the oxygen to the reagents, passing the water through a second transparent vessel, causing 5 light from a common source to pass through said vessels, causing the light which passes through said vessels to fall upon light-sensitive electric generative cells whereby potentials are maintained in opposed circuits, and continuously recording the ratio of variation in potentials between the circuits.
